ATTORNEY.

UNITED STATES PATENT OFFICE.

WILLIAM E. ROGERS, OF INDEPENDENCE, MISSOURI.

TRAIN-ORDER HOOP AND HOLDER THEREFOR.

Application filed June 23, 1925. Serial No. 39,153.

To all whom it may concern:

Be it known that I, WILLIAM E. ROGERS, a citizen of the United States, residing at Independence, in the county of Jackson and State of Missouri, have invented certain new and useful Improvements in Train-Order Hoops and Holders Therefor, of which the following is a complete specification.

This invention relates to the well known message holder used to place a train order in the hands of the engineer, conductor or other trainmen when the train does not stop at the station where the message is to be procured.

Ordinarily, an elliptical, wooden message carrier is used which has an extention integral therewith to be used as a handle. A wire spring holds the message tightly against the body of the carrier, and after the same has been removed by the trainman, the carrier is thrown down in the right-of-way where the station agent recovers it for further use. This method has proven unsatisfactory. The carriers are very often crushed under the train, lost in high weeds along the track, or carried so far that the agent can not go after it.

The present invention has for its primary object the provision of a holder for the message to be delivered as well as a means for releasably gripping the message holder.

Heretofore, a separate holder has not been used, and it is the further object of this invention to provide a holder for the train order hoop that may be kept at the station at all times and will always be ready for use.

A still further object of the present invention is the provision of a cheaply constructed hoop to be used in connection with the holder that may be made small enough to be retained by the trainman after his message is received and turned in at the end of his run. Due to the low cost, a great number of the hoops may be stored at each station, and the supply replenished from the terminal points once or twice a month.

An even further object of this invention is to provide a hoop holder having means for holding a plurality of order carrying hoops which may be rotated to the "presented" position in their proper sequence and as desired.

Minor objects will appear in the course of the detailed specification which sets forth

but one embodiment of the invention. In the accompanying drawing,

Figure 1 is a side view of a holder constructed in accordance with this invention and having but one additional hoop gripping member.

Fig. 2 is a section of the same taken on line II—II of Fig. 1.

Fig. 3 is an enlarged perspective view of the gripping jaws, showing their attachment to the handle.

Fig. 4 is a cross section of the upper end of the handle taken through the interlocking member, and

Fig. 5 is an enlarged side elevation of the message holding clip which is formed integrally with the body of the hoop.

In the drawing, wherein similar reference characters refer to like parts throughout the several views, the handle 6 of the holder may be provided at its one end with hoop engaging jaws 7, fastened to handle 6 by any suitable means such as members 8 which pivotally support jaws 7 at 9. The outwardly extending jaws 7 diverge inwardly as shown in Fig. 3, and are provided with grooves 10 into which fits the salient 11 of the message carrying hoop 12.

Each jaw 7 has a depending portion 13 integral therewith which engages the outer end of a spring or the like 14 held by handle 6. When a hoop is set between jaws 7, the operator's fingers force the same apart by drawing portions 13 toward handle 6 and depressing springs 14. These springs permit the removal of hoop 12 without the exertion of an excessive force or pull.

A clip for holding the paper 15, upon which the order is written, may be formed integrally with the hoop and to define a pair of loops 16 arranged in juxtaposition as shown in Fig. 5. The body of the hoop at this point may be spring wire to maintain the loops in their gripping relation, or the same may be separately formed and joined to hoop 12 in any suitable manner.

In placing a train order in the hands of a trainman through this particular method, it is generally necessary to have two or more copies of the order held by hoops, each of which are given to different men at locations along the train.

To fulfill this requirement without using more than one separate hoop holder, the device here shown has been constructed to embody this point of invention by having an

2
arm 17 pivotally mounted as at 18 and adapted to be held in the closed position by the ordinary spring 19, plunger 20 and detent 21 which structure has been clearly illustrated in Fig. 4. Various forms of structures may be used in making this head, and any means may be mounted upon handle 6 which presents any number of jaws 7 to hold any number of hoops 12.

10 The operation of the device is simple, and any one familiar with the art can readily see the advantages. As soon as the hoop 12, held by jaws 7 at the end of the handle 6, is snapped out of place by the engineer, the 15 holder of handle 6 swings arm 17 to the closed position where the hoop 12 carried thereby is presented in practically the same position as the former one and may be caught by the trainman farther toward the 20 rear of the train. The handle 6 is flattened near the top, and the use of a flat member 8 is desired in this particular structure to allow arm 17 to lie as close to handle 6 as possible.

25 It is understood that many changes and modifications may be made, and the invention is limited only by the scope of the appended claims.

What is claimed is:

30 1. A device of the kind described comprising in combination, a hoop holder and a message carrying hoop, said hoop having means for gripping a message and said holder including a pair of grooved and pivoted jaws converging toward each other as their outer ends are approached for releasably holding said hoop, the hoop being formed to present a salient having sides diverging away from each other at angles 35 corresponding to the angle of convergence of said jaws as their outer ends are approached and engageable by the grooves formed in the jaws of said holder.

40 2. A device of the kind described comprising in combination, a message carrying member comprising a hoop formed to present a message engaging clip and a salient having walls diverging away from each other as their outer ends are approached, and a holding means having yieldingly mounted jaws disposed at an angle toward each other as their outer ends are approached to correspond to the diverging angle of the 45 walls of said salient and adapted to releasably engage the walls of said salient when said hoop is being supported thereby.

3. In combination with a message carrying hoop provided with a salient having sides diverging away from each other as their outer ends are approached, a hoop 60 holder comprising a handle, a pair of jaws extending therefrom at angles and distances apart corresponding to the sides of said salient, means for pivotally attaching each of said jaws to said handle, said attaching 65 means being rigidly secured to said handle and having a pair of spaced apart walls extending beyond the end of said handle to be disposed on each side of the bottom of said salient when said device is holding a 70 hoop.

4. In combination with a message carrying hoop provided with a salient having sides diverging away from each other as their outer ends are approached, a hoop holder 75 comprising means for releasably holding said member including a handle, a pair of jaws pivotally mounted on said handle, said jaws being angled and spaced apart to correspond to the angle and distance apart of the sides 80 of said salient and resilient means for maintaining said jaws in engagement with the sides of the salient including a spring bearing directly against a portion of each jaw.

5. In combination with a message carrying hoop having a salient, a hoop holder comprising a pair of jaws each having a longitudinal groove extending the entire length thereof, said jaws being pivotally mounted at one end of a handle and means 85 for maintaining said jaws in engagement with the salient of said message carrying hoop, said jaws adapted to open and close in the major plane of the hoop to engage and disengage the sides of said salient 90 formed thereby.

6. A holder for hoops of the character described comprising a handle and a pair of jaws pivotally supported by said handle and with respect to each other, said jaws 100 each having a portion extending perpendicularly to said handle and a portion extending upwardly from said perpendicular portion, and a continuous groove running longitudinally of each jaw along the inner 105 face of each of said upwardly extending portions and continuing along the top of each of said perpendicularly extending portions.

In testimony whereof I hereunto affix my 110 signature this 16th day of June, 1925.

WILLIAM E. ROGERS.
